(57) **CLAIM**

The ornamental design for a solar siding panel, as shown and described.

DESCRIPTION

FIG. 1 is an isometric view of a solar siding panel showing the new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The solar siding panel is shown with a symbolic break in its length. The appearance of any portion of the article between the break lines forms no part of the claimed design.
